UNITED STATES PATENT OFFICE.

WILLIAM H. TAYLOR, OF NEW YORK, N. Y., ASSIGNOR TO REON BARNES,
OF SAME PLACE.

APPARATUS FOR MAKING CARBURETED-HYDROGEN GAS.

SPECIFICATION forming part of Letters Patent No. 256,406, dated April 11, 1882.

Application filed December 17, 1881. (No model.)

To all whom it may concern:

Be it known that I, WILLIAM H. TAYLOR, residing in the city, county, and State of New York, have invented certain Improvements in 5 Apparatus for Making Carbureted Hydrogen Gas, of which the following is a specification.

The object of this invention is the production of hydrogen gas from water and then carbureting it for illuminating or other purposes; 10 and the invention consists in arranging two grates in the lower portion of a gas-generating chamber for supporting two masses of anthracite coal or fixed carbon, which are separated by a bridge-wall, and are supported over a 15 chamber, into which air and superheated steam may be alternately forced, as will hereinafter appear.

The invention further consists in combining with said gas-generating chamber induction 20 and eduction pipes and valves for air, steam, and hydrocarbon in such a manner that the introduction and discharge of the substances required in the process may be performed alternately from one side to the other for continuing the operation, as will hereinafter appear.

In the drawings, Figure 1 represents a front elevation of the apparatus; Fig. 2, a section or with the front wall removed. Fig. 3 is a vertical section from front to rear on line *a b*. Fig. 25 4 is a horizontal section above the grate on line *c d*.

At *A* is the gas-generating chamber, formed of fire-brick, and of rectangular form, and about 30 twice as wide as it is deep or from front to rear, so that two masses of coal placed in it will have nearly square bases, though this is not essential. This furnace-chamber is surrounded with boiler-plate, as at *A'*, riveted at the 35 joints, and strengthened by bars of angle-iron, as at *A²* and *A³*, and the space between is filled with sand, as at *A⁴*, so that said chamber has great strength to resist internal pressure, and the sand serves as a non-conductor to the 40 internal heat. In the center of said chamber, and from front to rear, there is a division-wall, as at *B*, built of fire-brick or formed of slabs of the same, and extending nearly to the top of the chamber, so that it practically forms a 45 bridge-wall between the two grates at *C* and *D*

for supporting the masses of coal *E* and *F* over the ash-pits *G* and *H* in the bottom of the chamber *A*. Said ash-pits also serve as chambers for air from a fan or blowing-engine of some kind to assist the combustion, and also 55 as steam-chambers, as will be explained hereinafter.

At *K* and *L*, leading from the ash-pits, are pipes of metal lined with fire-clay or some similar refractory substance, to conduct off, first, 60 the smoke and products of combustion from the coal, and afterward the illuminating-gas.

The upper ends of these pipes are provided with a funnel at *M* and *N* into which fit valves or dampers *M'* and *N'*, of soapstone or similar substance, suspended on levers *M²* and *N²*, and provided with chains *M³* and *N³*, to raise and close like the dampers to a furnace-chimney, so that after the smoke has passed off they may be closed, and the gas may be turned into 70 the branches at *O* and *P*, and thence to the purifiers.

In the bridge-wall *B* are placed the super-heaters for the steam from which the hydrogen is obtained. These are made of metal, as 75 shown at *R*, and have a partition in each at *R'* to compel the steam from the boiler (not shown) entering at *S* to pass to the other end of the heater *R*, and return around the end of the plate or diaphragm *R'*, and down through 80 the pipes *S'* to another heater below, and so on through the several heaters to the discharge-pipe *T*, which enters the ash-pit below the grates. The coal is fed upon the grates in the chamber *A* through the funnels or chutes at 85 *U* in the arch, and they are furnished with caps having flanges at *U'*, that fit into recesses or grooves at *U²*, around the top of the funnels, into which sand or other substance is placed to form a seal to the caps to prevent the escape of gas from the chamber *A*. The air from the fan (not shown) is conducted through the main pipes *W* and branches *W'* and *W²*, leading down to the ash-pit or below the grates, and as shown above the furnace-doors 90 at *X*, and each of these branch pipes has a wing-valve or other equivalent that is connected by a lever, *Y*, on the stem of the valve *Y'*, to a sliding bar, *Y²*, which works in guides *Y³* on the front of the chamber *A*, and said bar 100

has a hand-hole or handle at one end, as at Y⁴, for the attendant to operate all the valves at once, and said valves are so set that when two of them are opened the other two are closed. 5 The hydrocarbon liquid is held in tanks at Z, placed above the chamber, so it may easily flow down through the pipes Z¹ and Z² into the upper corners or portion of the chamber A, and these pipes have stop-cocks, as shown at Z³, to control the flow of the liquid. 10 The operation is as follows: Both grates are supplied with a charge of coal, as represented at Fig. 2; but the fire is started under only one—say at D—to the mass of coal F, and the blast is turned on only under said grate and shut off the other. The damper at N' is closed and the one at M' is opened, so that the smoke, &c., from the coal at F pass over the bridge-wall at B and descend through the mass of 15 coal at E and down through the grate C into the ash-pit, and thence out through the pipe K, and escape at the funnel M or past the damper M', which is shown as raised. The blast is continued in this manner until the two 20 masses of coal are brought to an incandescent or highly-heated condition; but it is evident that the mass at E will be less heated than the other, to which the blast is first applied. The blast is now stopped entirely, and, the 25 damper at M' is closed, also the pipe K, by cock at K', and then superheated steam from the heaters R is turned on, but only under the grate C, so that it first enters the heated coal through the grate and at its lowest point of 30 temperature, or at least that point farthest from the blast. It then rises up through the mass of highly-heated coal to the top of the chamber A, and as it passes over the bridge-wall B meets with an incoming stream of the 35 hydrocarbon liquid from the tank Z through the pipe Z², when they intermingle with each other in a highly-vaporized condition, and then pass down through the mass of coal at F, which is the most highly heated of the two, and 40 thence down through the grate D and out through the pipe L to the branch P, leading to the purifier. This operation is continued in this direction until the quality of the gas upon examination shows that the heat 45 must be increased, when the steam and hydrocarbon liquid are both shut off and the airblast is again turned on to increase the temperature of the coal; but this time it is turned on under the grate C, or in the reverse direction, and the mass of coal at E is thereby first 50 raised to the higher temperature, and then the mass at F, and the smoke escapes out of the pipe at L and at the funnel N, the damper N'

being raised for that purpose and the cock at P' closed to permit the flow to the purifier. 55 After a sufficient degree of heat is produced in the two masses of coal, as before, then the blast is shut off and the superheated steam is again turned on, but under the grate at D, and it takes the reverse direction and passes 60 over the bridge-wall at B and meets with the stream of hydrocarbon at Z', and then descends through the mass of coal at E and the grate at C, and up the pipe K, out of the branch pipe at O, to the purifier, and thus, by alternately 65 reversing the blast and the supply of steam and hydrocarbon, the operation of making the gas is rendered nearly continuous in the same chamber at A. 70

It is evident that various forms and the arrangement of many of the parts may be introduced without departing from the nature of my invention; and therefore

I desire to claim—

1. In a gas-generating apparatus, the combination of a double-grated chamber, adapted for holding two masses of coal separated by a bridge-wall, with a smoke stack or flue connected to a chamber under each grate and provided with dampers at their outer ends, whereby the products of combustion may be conducted from both grates alternately, as hereinbefore set forth. 80
  2. In a gas-generating apparatus, the combination of a double-grated chamber having a bridge-wall between the grates and two smoke-flues, one connected to the space under each grate, and provided with a damper or valve at their outer ends, with the branches O and P, for conducting the gas from the grates alternately, as hereinbefore set forth. 90
  3. In a gas-generating apparatus, the combination of the double-grated chamber A, bridge-wall B, smoke-flues K and L, dampers M' and N', branches O and P, and inlet-pipes Z¹ and Z², whereby the operation of producing the carbureted gas may be conducted alternately, as hereinbefore set forth. 100
  4. In a gas-generating apparatus, the combination of the double-grated chamber A, having a bridge-wall, B, with chambers below the grates, in combination with the steam, air, and smoke pipes for each grate, as hereinbefore set forth. 105
- In witness whereof I have hereto subscribed my name and affixed my seal in the presence of two subscribing witnesses.
